[57] CLAIM

The ornamental design for a terminal housing, substantially as shown and described.

DESCRIPTION

FIG. 1 is a front perspective view of the terminal housing showing our new design;

FIG. 2 is a top plan view thereof on an enlarged scale;

FIG. 3 is a front elevational view thereof on an enlarged scale;

FIG. 4 is a side elevational view thereof on an enlarged scale, the opposite side being a mirror image;

FIG. 5 is a rear elevational view thereof on an enlarged scale.

The keys are shown in broken lines in FIG. 2 for illustrative purposes only.
